Specification for Design.

Patented Aug. 27, 1912.

Application filed April 21, 1910. Serial No. 556,906. Term of patent 3½ years.

To all whom it may concern:

Be it known that I, HERBERT A. AUSTIN, a citizen of the United States, residing at Roxbury, in the county of Suffolk and State of Massachusetts, have invented a new, original, and ornamental Design for Hair Ornaments or Bandeaux, of which the following is a specification, reference being had to the accompanying drawing, forming part thereof.

The figure is a perspective view of a hair ornament or bandeau, showing my new design.

The structure may be said to comprise a barrette 1, which, as will be seen, is curved lengthwise and provided with a series of

cross-bars 2, through which a ribbon 3 is threaded, any number of the bars 2 being exposed as desired. One end of the ribbon is secured to a smaller barrette or combined barrette and slide 4, which is likewise provided with a series of cross-bars 4, while the other end of the ribbon is attached to a similar barrette or slide 6, having cross-bars 7.

I claim:

The ornamental design for a hair ornament or bandeau, as shown and described.

HERBERT A. AUSTIN.
